DESIGN FOR A HAMMOCK BODY OR THE LIKE

Andrew J. Kolonics, New York, N. Y.

Application January 29, 1946, Serial No. 126,056

Term of patent 3½ years

(Cl. D5—1)

To all whom it may concern:

Be it known that I, Andrew J. Kolonics, a citizen of the United States of America, residing in the city of New York, county of Kings, and State of New York, have invented a new, original, and ornamental Design for a Hammock Body or the like, of which the following is a specification, reference being had to the accompanying drawing, forming part thereof, in which the figure shown is a face view of a hammock body or the like, showing my new design.

I claim:

The ornamental design for a hammock body or the like, substantially as shown.

ANDREW J. KOLONICS.
